UNITED STATES PATENT OFFICE.

IDA SHERMAN COWLES, OF WAVERLY, PENNSYLVANIA.

DRAWER OR SHELF LINING.

1,327,755.

Specification of Letters Patent. Patented Jan. 13, 1920.

Application filed March 15, 1918. Serial No. 222,600.

To all whom it may concern:

Be it known that I, IDA SHERMAN COWLES, a citizen of the United States, residing at Waverly, in the county of Lackawanna and 5 State of Pennsylvania, have invented new and useful Improvements in Drawer or Shelf Linings, of which the following is a specification.

This invention relates to an improvement 10 in drawer or shelf linings, proposing a lining which is especially intended for domestic use in connection with the drawers of articles of furniture, such as bureaus, chiffoniers and the like or with shelves of cupboards, wardrobes and similar cabinets.

The principal objects of the invention are 20 to provide a lining which may be easily and quickly adjusted to fit the drawer or shelf with which it is to be used, which, when fitted in position, shall not be liable to displacement, which, despite its capacity for adjustment, may carry out or preserve certain designs of ornamental character, and which may be manufactured and sold at 25 very low cost.

With the above objects in view the invention consists generally of a lining which is made in sections adapted to be fitted in the respective corners of a drawer or shelf and 30 to be secured together as fitted whereby to provide a single continuous lining sheet which conforms to the dimensions of said drawer or shelf and presents an even, regular, and unbroken surface which may bear 35 ornamental figures or designs whose esthetic value will be preserved in connection with any adjustment of the lining.

An embodiment of the invention is illustrated in the accompanying drawings, where- 40 in—

Figure 1 is a bottom plan view of the sections of the lining, showing them spaced from one another and in the relation of their normal adjacency.

45 Figs. 2 and 3 are plan views of the lining as applied to two different drawers which vary from one another in length and width.

Fig. 4 is a sectional view on the line 4—4 of Fig. 2. In this figure it has been necessary to somewhat exaggerate the thickness of the sections of the lining.

Similar characters of reference designate corresponding parts throughout the several views.

55 The lining consists of four sections which

are differentiated from one another by the letters A, B, C and D, and, as manufactured, will preferably bear distinguishing indicia applied to their underfaces. These sections are counter-parts, as to outline and dimensions and are of rectangular form; they differ structurally from one another, however, as regards certain features of their underfaces which are employed to effect their mutual connection in adjusted relation whereby the sections will constitute a single lining sheet.

Thus the under face of the section A may be perfectly plain; the under face of the section B has a strip or zone 1 of mucilage or 70 similar adhesive along its inner side or longitudinal edge; the under face of the section C has a strip or zone 2 of adhesive material along its inner end or transverse edge; and the under face of the section D has strips or 75 zones 3 and 4 of adhesive material along its inner side or longitudinal edge and its inner end or transverse edge.

In fitting the lining to a drawer the sections are arranged with their faces shown 80 in Fig. 1, downward and the procedure is as follows: The section A is first placed squarely in the upper or rear right hand corner of the drawer; then the section B is placed in the lower or front right hand corner of the drawer and its inner side or longitudinal edge is laid over the section A and pasted to it by means of the strip or zone of adhesive material 1; the section C is then 85 fitted in the upper or rear left hand corner of the drawer and its inner end or transverse edge is laid over the section A and pasted to it by means of the strip or zone of adhesive material 2; and the section D is then fitted in the lower or front left hand corner of the drawer with its inner side or longitudinal edge laid over the section C and its inner end or transverse edge laid over the section B to which the said inner side and end edges are then secured by means 90 of the zones of adhesive material 3 and 4. It will thus be seen that the adjustment of the sections relatively to one another whereby they conform to the dimensions of the drawer is an incident of the fitting of said 95 sections squarely in the corners of the drawer in the manner described. When the sections have been secured together by means of the zones of adhesive material 1, 2, 3 and 4 they constitute a single continuous lining 100

sheet which is not liable to displacement and whose upper or exposed surface is even, regular, and without interruption. The increased thickness of the sheet in the portions 5 where the sections overlap is obviously without any appreciable effect on the regularity or evenness of the upper or exposed surface of the sheet.

The word "longitudinal" as applied to the 10 edges of the sections refers to the edges which will lie within the dimension taken between the end walls of the drawer and the word "transverse" as applied to the edges of the section refers to the edges which will 15 lie within the dimension taken between the front and rear walls of the drawer.

The upper faces of the sections may bear 20 any suitable ornamental figures or designs selected to provide a composite scheme of ornamentation throughout the sheet, regardless of the dimension which the sheet may have in consequence of the adjustment of said sections to a particular drawer or shelf. As an example of this the drawings 25 show the upper face of the sheet as having a marginal border X and a field Y within the border and which may be provided with small ornamental figures. It will be noted that the form and relation of the border and 30 field will not be impaired by variations in the dimensions of the sheet.

While the ornamentation of the sheet may 35 be of any desired character it is preferred that it include the border, as shown, since such a border assists in properly locating the sections with relation to one another and to the sides and ends of the drawer or shelf.

While the sections of each lining will be 40 counter-parts, it will be understood that the dimensions of said sections may be selected to provide for any desired range of adjustment and that in any case the range of adjustment will be considerable whereby a lining may be fitted to a drawer whose 45 area is nearly equal to the aggregate area of the sections or to a drawer whose area is only slightly greater than the area of a single section.

Having fully described my invention 1
claim—

1. An adjustable lining for drawers or shelves composed of four rectangular sections which are counterparts in size, the first of which may have a plain underface and the second of which is provided with a 55 strip of adhesive material along the inner longitudinal edge of its underface, the third with a strip of adhesive material along the inner transverse edge of its underface and the fourth with strips of adhesive material 60 along both the inner longitudinal and inner transverse edges of its underface.

2. An adjustable lining for drawers or shelves composed of four rectangular sections which are counterparts in size, the first 65 of which may have a plain underface and the second of which is provided with a strip of adhesive material along the inner longitudinal edge of its underface, the third with a strip of adhesive material along the inner 70 transverse edge of its underface and the fourth with strips of adhesive material along both the inner longitudinal and inner transverse edges of its underface, the said 75 sections having such ornamentation applied to their upper faces as will facilitate the proper location of the sections relatively to the sides and ends of the drawer or shelf to which the lining is to be fitted.

3. An adjustable lining for drawers or shelves comprising four counterpart rectangular sections, certain of which have their underfaces gummed whereby the sections may be fitted in the respective corners of a drawer or shelf, and secured together as 85 they are fitted to provide a single and continuous lining sheet whose dimensions will conform to the surface dimensions of said drawer or shelf.

In testimony whereof I have hereunto set 90
my hand in presence of two subscribing wit-
nesses.

IDA SHERMAN COWLES.
